UNITED STATES PATENT OFFICE.

FRANK D. CARNEY, OF STEELTON, PENNSYLVANIA.

RAILWAY-RAIL.

1,188,149.

Specification of Letters Patent. Patented June 20, 1916.

Application filed April 7, 1915. Serial No. 19,695.

To all whom it may concern:

Be it known that I, FRANK D. CARNEY, a citizen of the United States of America, residing at Steelton, in the county of Dauphin 5 and State of Pennsylvania, have invented certain new and useful Improvements in Railway-Rails; and I do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification. 15

My invention relates to the structure and configuration of railway rails designed to carry heavy traffic.

Railway traffic loads have been constantly 20 increasing during recent years, so that the load on each wheel of a freight car has within the past decade been practically doubled.

With the increase in the load on the rolling stock the rails have been increased in 25 size somewhat, that is, in the weight per yard, so as to use a stronger and larger rail to sustain these increasing loads. But this increase in the size and weight of the rails has not been proportionate to the increase in 30 the loads they stand, so that many railroads have trouble with their rails from time to time.

Standard gage roads carrying freight loads now customarily use rails varying 35 from 100 to 150 pounds per yard, 120 pounds per yard at present being considered standard weight, but these sizes have not yet been found adequate to stand the increased load.

Recently rails have been used containing 40 nickel and chromium as toughening and hardening elements, and it is with such rails that I have experimented with a view to increasing their durability and strength; but, while rails containing nickel and chromium 45 would have higher physical qualities, it is not absolutely necessary to use steel of this composition for the manufacture of heat-treated rails. The addition of chromium and nickel to the metal, while adding some- 50 what to the cost, is not so expensive as an equivalent increase in the quantity of steel in the rail.

It is well known that the tempering of 55 steel increases its durability, and while this is feasible with wire and small sheets, as saw blades and tool steels, the simple cool-

ing and quenching of a rail or other large symmetrical shapes cannot be carried out in this manner, on account of the irregularity of cooling and the excessive internal strains 60 set up thereby. In order to be practicable, the tempering operation must be one that does not add too much to the cost of the rail by reason of change of shape and cost of manipulation. 65

In carrying out experiments of tempering rails of usual configuration of cross section it was found that upon quenching the hot rails as they left the last roll pass, preparatory to drawing the temper by re-heating, 70 cracks would develop along the fillets joining the head and base of the rail to the web. These cracks extended in some cases quite a distance into the web and base. The problem I have solved is to obtain a rail section 75 in which the metal is so distributed as to avoid these cracks due to quenching. The drawing of the temper after quenching I found to have no injurious effect on the rail, as the temperature to which the rail is re-heated is not so high as the temperature of the rail when ready for quenching after leaving the rolls. After many experiments I have succeeded in avoiding the formation of 80 these quenching cracks, which necessitates a 85 slight increase in the amount of metal in the usual rail section, and I have found from my experiments that a rail capable of being so tempered must fulfil the following conditions: The rail must have a cross section of 90 such configuration that the area of the base must be equal to or greater than the area of the head; the radii of the top fillets, namely those joining the head and web, must be equal to or greater than one-eighth of the 95 square root of the area of the section of the rail as measured in inches, and the radii of the bottom fillets, namely those joining the web and base, must be equal to or greater than one-sixteenth of the area of the section, 100 measured in inches.

I believe that I am the first to make a rail capable of being quenched and the temperature drawn, the elements of whose section are designed to withstand the internal 105 strains resulting from the quenching.

I have chosen for illustration in the drawing a rail whose weight and shape approximate the standard untempered rail now in use, and have shown the metal distributed 110 according to my invention.

The accompanying drawing illustrates a

section of a full sized 121 pound rail, the area of the entire section being 11.90 square inches. The top fillets d shall have a radius not less than one-eighth of the square-root of 11.90; that is, one-eighth of 3.4496, or 0.431. This fillet radius has been chosen slightly greater than this, namely five-eighths of an inch, to facilitate fishing and as a factor of safety. The radius of the lower fillet e shall not be less than one-sixteenth the total area, namely one-sixteenth of 11.90, or .744, and for the reasons given above has been chosen slightly greater than the limit, namely 1.125 inches. The area of the head, a , of the rail is 4.42 square inches, and the area of the base c 4.94 square inches.

I claim—

1. A steel railway rail constructed for tempering by quenching, having a cross section whose top fillets have a radius at least equal to one-eighth the square root of the total area of the section of the rail measured in inches.
2. A steel railway rail constructed for tempering by quenching whose bottom fillets have a radius of at least one-sixteenth the total area of the section.
3. A steel railway rail constructed for

tempering by quenching, having a cross section whose base is at least equal in area to the head and whose top fillets have a radius at least equal to one-eighth the square root of the area of the section measured in inches.

4. A steel railway rail constructed for tempering by quenching, having a cross section whose base is at least equal in area to the area of the head and whose bottom fillets have a radius of at least one-sixteenth the total area of the section.

5. A steel railway rail constructed for tempering by quenching, having a cross section whose base is at least equal in area to the area of the head, whose top fillets have a radius at least equal to one-eighth the square root of the total area of the section measured in square inches and whose bottom fillets have a radius at least equal to one-sixteenth of the total area of the cross section measured in square inches.

In testimony that I claim the foregoing as my invention, I have signed my name in presence of two subscribing witnesses.

FRANK D. CARNEY.
